UNITED STATES PATENT OFFICE.

CHARLES D. WHITE, OF NORWICH, CONNECTICUT.

SPINNING-FRAME.

1,280,922.

Specification of Letters Patent.

Patented Oct. 8, 1918.

Application filed September 17, 1917. Serial No. 191,700.

To all whom it may concern:

Be it known that I, CHARLES D. WHITE, a citizen of the United States, residing at Norwich, in the county of New London, in the State of Connecticut, have invented a certain new and useful Improvement in Spinning-Frames, of which the following is a specification, reference being had to the accompanying drawings.

10 This invention relates particularly to the drawing rolls and twisting mechanism of spinning machinery of the type commonly used in cotton mills; the immediate object of said invention being to overcome a common tendency on the part of the yarns to break at the point where they leave the so called "front" rolls, as I will explain more fully hereinafter.

The annexed drawings, when taken in connection with the specification, will aid in explaining my invention, Figure 1 of said drawings being mainly a transverse, sectional view of one set of drawing rolls and an elevation of a portion of one of the bobbins. Fig. 2 is a front side view of the special carrier rolls *g* and shaft *g'* which forms one elementary feature of my present improvement, and Fig. 3 is a relatively enlarged view of a section of said shaft.

20 Referring to these drawings, the letter *a* indicates a portion of the top rail of a ring spinning frame and *b* denotes a portion of a bobbin which, it is assumed, is mounted on a spindle in the usual, or any other practical manner and having coöperating with it the customary ring traveler *c*. Fixedly secured to the frame *a* are brackets *d* in which are revolvably mounted the customary drawing rolls which consists, as here shown, of 30 three pairs of rolls known usually as the drawing rolls *e* and the front or delivery rolls *f*.

From these front rolls the yarns pass ordinarily over or through a guide eye and 40 thence to the ring-spinning mechanism and take-up bobbin *b*, the arrangement of the described parts being ordinarily such that the yarn, after being freed from the biting action of the periphery of the front roll, leads downward and thus remains in contact with the lower front roll for a considerable distance instead of being immediately released from the biting action of said front rolls, and I have found, by long experience, 50 that such contact with the lower front roll operates frictionally, as a drag, to hinder

the twisting of the untwisted roving at that point; thus leaving the yarn weakest at that point and liable to break. In order to overcome this objectionable result I have provided simple but effective means whereby the drawn yarn is delivered from the front rolls *f* through a path that alines with the path of the roving as the latter passes between the several pairs of rolls instead of being directed slightly downward, as heretofore, and this result I attain by providing what I term a "carrier" roll *g* which is journaled in a special bracket *h* which is secured to the bracket *d* by screws *h'* as here shown.

As the yarn (indicated by the letter *x*) leaves the front rolls it continues in a right line of movement to the carrier roll *g* and thence downward to the twisting mechanism and take-up bobbin. The yarn thus passes directly and freely from the point where it is released from the bite of the front rolls to the described carrier roll with no tendency to drag frictionally along the upper portion of the lower roll, in the objectionable manner first above described by me.

The carrier roll shaft *g'* is driven (in the machine of the drawing) by means of a gear *i* on the lower front roll *f* which meshes with a like gear *k* on the carrier roll shaft, this construction being such that the carrier rolls are caused to revolve in the opposite direction from the said lower front rolls, that is to say against the direction in which the yarn is traveling and, by preference, at a rotative speed substantially the same as the front rolls.

The operation of the drawing rolls and front rolls, as well as of the spinning and winding on bobbins, may be precisely the same as heretofore. During the spinning operation, however, the twisting mechanism acts directly only upon that portion of the yarn that extends downward from the carrier roll *g*, while the torsional strain of the yarn is relieved at its upper portion, (where it contacts with the carrier roll), by reason of the reverse rotative movement of said carrier roll; the twist being in effect carried over and past the point of contact with said roll and is thus permitted to work back to the biting point between the two front rolls.

The carrier roll *g* is preferably fluted longitudinally and flanged, as illustrated, in order that the twist in the yarn may then more readily adjust itself (by slipping tor-

sionally) as the twist is transferred, or extended, to that portion of the yarn between the carrier roll and the front rolls.

By the aid of the carrier roll located as described the tendency on the part of the yarn to break is materially reduced, as I have demonstrated by a practical and continued trial of such rolls, and my described improvement has the decided advantage that it can be added to spinning frames as now commonly constructed, with very little cost. The yarn is twisted to the bite of the front rolls, the thread-board guides, heretofore necessary, are done away with and, owing to the evenness of twist and elimination of friction, a traveler double the customary weight can be used; thus making it possible to put about 25% more yarn on the bobbin. Another decided advantage derived by the use of my described carrier roll is in the fact that no lint bunches are formed in the yarn, since the elimination of the thread boards allows all lint and dust to drop to the floor instead of lodging on said thread boards.

The described construction and action makes it possible to maintain the twisted yarn clear back to said biting point instead of leaving, at all times, a short portion of the untwisted, and relatively weaker, roving wrapped around a portion of the perimeter of the lower front roll and, in order

to produce the best results, it is desirable that the reversely rotating carrier roll and the alining yarn, shall be used in substantially the combination shown and described. 35

Having thus described my invention, I claim:—

1. In a spinning frame, a carrier roll located between the drawing rolls and the twisting mechanism, and means for revolving said roll in a direction opposite to the movement of the yarn; the position of said carrier roll being in alinement with both the spindle, and the bite of the front draft roll and at a considerable distance above the top 40 of the spindle whereby the use of a much longer bobbin will be permitted than is possible by the usual location of the guide wire attached to the fly board.

2. In a spinning frame, a longitudinally fluted carrier roll located between the drawing rolls and the twisting mechanism; the position of said carrier roll being in alinement with both the spindle and the bite of the front draft roll and at a considerable 50 distance above the top of the spindle whereby the use of a much longer bobbin will be permitted than is possible by the usual location of the guide wire attached to the fly board. 55

CHARLES D. WHITE.
